UNITED STATES PATENT OFFICE.

JOSEPH VINCENT ROBINSON, OF SALEM, OREGON.

AUTOMATIC INTERLOCKING COUPLING.

1,181,481.

Specification of Letters Patent. Patented May 2, 1916.

Application filed October 7, 1909, Serial No. 521,445. Renewed May 16, 1911. Serial No. 827,514.

To all whom it may concern:

Be it known that I, JOSEPH VINCENT ROBINSON, a citizen of the United States, residing at Salem, in the county of Marion 5 and State of Oregon, have invented certain new and useful Improvements in Automatic Interlocking Couplings, of which the following is a specification.

This invention relates to automatic air 10 and steam couplers for railway trains and is an improvement on the mechanism described and claimed in my Re-issue Letters Patent No. 13,138—dated July 26, 1910.

This present invention comprehends a 15 number of specific details of construction hereinafter fully described and claimed and illustrated in the accompanying drawings, in which:

Figure 1 is a front elevation of one of the 20 coupling heads in the position which it occupies when carried by a railway car; Fig. 2 is a vertical longitudinal section on the line 2—2 of Fig. 1; Fig. 3 is a horizontal longitudinal section on the broken line 3—3 25 of Fig. 1; Fig. 4 is a rear elevation of one of the coupling heads, parts being in section; Fig. 5 is a side elevation of the bracket connected to the draw bar and showing the upper parts of a support to which one of the 30 heads is connected; Fig. 6 is a plan view of said bracket detached and showing the movable extension of said bracket swung about so as to expose the face plate of the coupling head carried thereby for the purpose of repair; Fig. 7 is a transverse vertical sectional detail on the line 7—7 of Fig. 5; Fig. 8 is a detail view of the locking pawl employed in connection with the adjusting means, and Fig. 9 is a vertical longitudinal sectional detail on the line 9—9 of Fig. 1.

Throughout the following description and on the several figures of the drawings similar parts are referred to by like reference characters.

45 Referring particularly to the first figures of the drawings, the numeral 10 indicates a coupling head adapted to coöperate with a similar coupling head carried by the next car, said coupling heads being substantially 50 alike and adapted to coöperate with each other automatically and simultaneously with the operation of the usual automatic train couplers. Said coupling heads 10, as is usual in this class of inventions, carry pipe 55 sections for the purpose of coupling the sig-

nal air, brake air, and steam pipe connections. Each coupling head 10 comprises a face plate 11, of any suitable general configuration, but maintained normally in substantially vertical position. Any suitable 60 means may be employed to carry the head as a whole in a substantially horizontal position in order to maintain the face plate in the position stated. The form of the face plate indicated is substantially elliptical so 65 as to provide openings for the three pipe connections in a substantially vertical line, although it is to be understood that any other form of face plate and disposition of pipe openings might be resorted to as might 70 be found expedient. Extending forwardly from each of said face plates 11 are a plurality of guide members 12. Said members are preferably two in number for each head and extend from diagonally opposite portions 75 of the face plate forwardly at a right angle thereto for a certain distance and thence are curved outwardly so that the extreme distance between the outer points 12' of said members is considerably greater than the 80 width of the face plate. These guide members are commonly employed in this art for the purpose of causing the coupling heads carried by two cars that are being coupled to properly align with each other, even 85 though one of the heads may be normally carried out of alignment with the other. The guide members at those portions where they are connected with the face plate extend substantially half way around the 90 same so that when the two heads are coupled the abutting face plates will be practically surrounded by said members.

From the nature of this invention it will 95 be appreciated that since the coupler is designed to be automatic in its operations it is necessary to insure that by no possibility the coupler may be disturbed by any lateral force when it is supposed to be coupled. It is customary for the coupling heads to be 100 spring cushioned so as to insure a proper degree of tension the one against the other for the purpose of insuring tight joints, and when the cars are passing around curves 105 or when the coupler is subjected to a severe lateral blow from any source there is a tendency for one side of the coupler to separate or buckle, tending to cause a leakage, in devices of this character heretofore proposed.

One of the objects of this invention is to provide the coupling heads of such peculiar form and construction as to make it an impossibility for any such separation to take place. To this end those portions of the face plate 11 between the guide members 12 are provided with rearwardly extending flanges 13, which are coextensive with the right angled portions 12^a of the guide members 12 and with which they coöperate when the coupler is coupled. This construction insures a broad interlocking bearing contact between the two coupling heads, said bearing surfaces being parallel to the axis of the system. I am aware that it has heretofore been proposed to provide guide members on coupling heads which are right angled for a short distance with respect to the face plates, but such construction has heretofore been employed only for the purpose of preventing lateral displacement of one head with respect to the other, and so far as I am aware I am the first to construct a coupling head with a flange or set of flanges extending rearwardly from the face plates for the purposes above set forth.

Additional interlocking means of any suitable character may be employed in connection with the means above described. To this end I provide each coupling head with one or more lugs which coöperate with corresponding sockets in the other head. Said lugs and sockets may be of any suitable form and may be located at any desired place or places. As shown however a lug 14 is formed integral with one of the guide members 12 near its lower edge and on its inner face, said lug being located adjacent to the straight portion 12^a of said member, but is slightly shorter than said straight portion in order to insure that the approaching coupling heads may be properly aligned by the guide members before the lug is caused to enter the socket 15 adapted to receive it. The outer end 14' of said lug is slightly rounded to prevent any possibility of its striking the walls of the socket. The lugs and complementary sockets are arranged longitudinally of or parallel to the longitudinal axis of the coupler. Each lug is of substantially uniform thickness throughout its length, but as appears in side view is tapered outwardly from its base toward said rounded end. Again, each of the lugs is provided with oppositely arranged shoulders 14^a which interlock with the dovetailed or under-cut walls of the complementary socket into which it is received in the other head, the socket being of the same form as the lug. Each guide member 12 is provided with another lug 16 adapted to coöperate with a socket 17 of the opposing head. The lugs 16 are tapered and of the same general characteristics as the above described lugs 14, but 35 may be smaller in size.

At 18, 19, and 20 are indicated the signal air, brake air, and steam heat connections, respectively. In each of said connections is arranged a suitable gasket, those shown at 18' and 19' being preferably of rubber or other suitable compressible material each of which is introduced from the outside of the face plate 11. The gasket employed in connection with the steam heat connection, however, must be of peculiar construction in order to prevent the steam from damaging the same by immediate contact. To this end there is employed a thimble 21 having threaded connection at 21' with the face plate, the same being operated by the application of a spanner to the inwardly projecting lugs 21^a. The gasket proper 22 surrounds the thimble and is connected thereto by a rib 21^b extending outwardly from the outer face of the thimble and into a groove 22' in the gasket. When the thimble is separated from the face plate the gasket 22 may be applied thereto, being sufficiently flexible for the purpose of passing over the rib and when the thimble is screwed into place the gasket will be carried thereby, fitting into a socket or rabbet 23. The outer edge of the gasket should project sufficiently far beyond the face of the face plate to make a proper steam connection, but the outer edge of the thimble may be substantially flush with that portion of the face plate which surrounds the said socket or rabbet 23. In order to insure the coupling heads from rocking laterally one upon the other it is important that there should be provided a shallow flange or rim 24 extending substantially around the edge of each face plate, and said rim 24 may also be extended around the steam heat seat. It will be seen by this construction of the steam heat connection that when the two coupling heads are connected the gaskets 22 will be compressed substantially within the space between the thimbles and the face plates, and thereby they will be protected by the thimbles from steam contact.

As indicated in Figs. 1 and 5 the means for supporting the coupling heads consists of a bracket 25 adapted to be rigidly and permanently connected to the lower side of the draw bar 26 by means of bolts or screws 27. The bracket is provided along its lower portion with upwardly extending hook shaped flanges 25' which are adapted to coöperate with the upper ends of a pair of jaws constituting a rigid support or abutment 28. The two members of the support are adapted to be gripped to the bracket 25 by means of a pair of bolts 29 under ordinary operative conditions. Said support carries the head 10 at its lower end, said head being mounted therein for universal movement by means of a ball and socket connection 30. Said head is maintained normally in a horizontal position by means of a spring 31.

31 positively connected at one end to the support and at the other end to the rear face of the head face plate.

In devices of this character it is essential 5 for practical purposes that there be means provided whereby the trainman may readjust one or the other of the coupling heads intermediate the ends of a train without disturbing the engineer or uncoupling the cars. 10 The occasion for such adjustment may arise from leakage due to insufficient compression or tension of the spring 31 or it may arise from the fact that one or more of the packing gaskets may be defective by reason of 15 long usage or otherwise. It is important therefore that the trainman upon discovering a leak may tighten the coupling or if necessary to disconnect the same in order to gain access to the packing rings to re- 20 place or renew the same. I have therefore devised a means for moving the support 28 longitudinally of the bracket 25, such means being illustrated as including a rack 25^a provided along the lower edge of the bracket 25, and coöperating with said rack is a pinion 32 journaled transversely in said support 28. The pinion 32 is provided on one side with a short trunnion 33 journaled in one of the jaws of the support and on the 30 other side with a trunnion 34 extending through the other jaw of the support, the extreme end of the latter trunnion being formed polygonal at 34' for the application of a cranked wrench or other implement 35 whereby the pinion may be operated powerfully. The end 34' of said trunnion may conveniently be formed of the same size and configuration as the nuts of the bolts 29 so that the same wrench may be applied to 40 either successively. A pawl 35 is carried by one of the jaws of the support 28 and is seated therein in a socket 35^a for a limited amount of pivotal movement, the hub of the pawl preferably being in contact with 45 the circular wall of said socket. The point of the pawl coöperates with a ratchet 36 formed upon or adjacent to the trunnion 34. If it is found necessary to adjust the coupling head or tighten the connection the 50 trainman will apply his wrench to loosen the bolts 29 and then apply his wrench to the trunnion and turn the same in the direction of the arrow *a*, Fig. 5, causing the support 28 to be moved as far as necessary toward the left and thereby increasing the tension of the spring 31. If, however, it 55 is found necessary to repack the joints the operator will apply his wrench to the trunnion 34 and after lifting the pawl 35 out of engagement with the ratchet wheel he will move the support and head bodily rearwardly along the bracket 25 sufficiently far to gain access to the face plate. This operation may be carried out in various ways, but 60 as shown herein I provide an extension 37 and pivot the same to the main portion of the bracket by means of a bolt or pin 38 passed downwardly through a lug 38 and a pair of ears 40 and 40', said ears being integral with the extension 37 and the latter 70 of which may be screw threaded to receive the threaded lower end of said pin 38. The lower portion of the extension 37 should conform to the similar portion of the main portion of the bracket 25 so that the support 75 28 may pass from one to the other. Upon movement of the support 28 from the rigid portion of the bracket 25 rearwardly upon the extension 37 the support and head carried thereby may be swung around upon the pivot pin 38 as a center so as to bring the face plate 11 into easy position for operation, or in other words in a position in which the longitudinal axis of the support and head carried thereby is substantially 80 transverse to the axis of the car. It will be understood that the length of the extension 37 and its relation to the rigid portion of the bracket will be such that the guide members 12 of the heads will permit such 85 pivotal movement. After repairing or repacking the gaskets the extension 37 will be restored to its normal position in alignment with the rigid portion of the bracket 25 and the support 28 will be moved along 90 the same, either by hand or the wrench until resistance is encountered by the springs. Upon the application of force through the wrench the coupling head will be completed 95 at any desired degree of tension, the pawl 100 maintaining such tension temporarily until the bolts 29 are again tightened. It is to be noted also that the position and form of the support 28 with respect to the head are such as to cause the compression on the head 105 to tend to tilt the support upon the bracket thereby increasing the connection between the support and the bracket by a gripping effect.

Having thus fully described the invention 110 what I claim as new is:

1. In an automatic coupler for railway train pipes, the combination of a pair of heads, each of said heads comprising guide members for coöperation with the guide 115 members of the other head, said guide members being provided with lugs, and each head being further provided between its guide members with sockets to receive the lugs of the other head, substantially as set 120 forth.

2. In an automatic coupler for railway train pipes, the combination of a pair of heads, each of said heads comprising guide members for coöperation with the guide 125 members of the other head, lugs connected to said guide members on their inner faces, and each head being provided along its edges between the guide members with sockets to receive the said lugs of the other head. 130

3. In an automatic coupler for railway train pipes, the combination of a pair of heads, each of said heads comprising guide members for coöperation with the guide members of the other head, said guide members being provided on their inner surfaces with tapered lugs arranged parallel to the axis of the coupler, and each head being further provided along the edges thereof between the guide members with dovetailed tapered sockets to receive the lugs of the other head.

4. In an automatic coupler for railway train pipes, the combination of a pair of heads, each head comprising a face plate, a plurality of guide members extending forwardly from the face plate at a right angle thereto and thence curving outwardly, and a plurality of flanges extending rearwardly from the portions of the face plate between the guide members for coöperation with the right angled portions of the guide members of the other head, substantially as set forth.

5. In an automatic coupler for railway train pipes, the combination of a pair of heads, each head comprising a face plate, a plurality of guide members extending forwardly from the face plate at a right angle thereto and thence curving outwardly, a plurality of flanges extending rearwardly from the portions of the face plate between the guide members for coöperation with the right angled portions of the guide members of the other head, and each of said heads being further provided with tapered lugs and sockets arranged parallel to the axis of the coupler to receive and interlock with complementary parts of the other head, substantially as set forth.

40 6. In an automatic pipe coupler for railway cars, the combination of a coupling head, a bracket, a support for the head connected to said bracket, means for sliding the support longitudinally on the bracket, and means for causing the support to grip the bracket.

7. In an automatic pipe coupler for railway cars, the combination of a fixed bracket, an extension member pivoted to said fixed bracket so as to aline therewith, a support mounted upon said fixed bracket and movable therefrom upon said pivoted extension, a coupling head carried by the support, and means to positively adjust the support and head along the fixed bracket and extension.

55 8. In an automatic coupler of the character set forth, the combination of a fixed bracket, an extension connected thereto on a vertical pivot so as to aline with the fixed bracket or to assume a position at an angle thereto, a support carried by the fixed bracket and movable therefrom upon the pivoted extension when the latter is in alinement with the fixed bracket, a coupling head carried by the support, and power means for

adjusting the support and head along the fixed bracket and its extension.

9. In an automatic train pipe coupler for railway cars, the combination of a coupler head, a support therefor, adapted to be adjusted transversely to the longitudinal axis of the car and means for moving the head longitudinally of the support. 70

10. In an automatic train pipe coupler for railway cars, the combination of a coupler head, a support therefor, means for adjusting the coupler head relative to said support and means for shifting said support and coupler head transversely to the longitudinal axis of the car. 75

11. In an automatic train pipe coupler for railway cars, the combination of a support, a coupler head adjustably mounted on said support, and means for shifting said support transversely to the longitudinal axis 85 of the car.

12. In an automatic train pipe coupler for railway cars, the combination of a support, a coupler head yieldingly carried on said support, and means for shifting said support transversely to the longitudinal axis 90 of the car.

13. In an automatic train pipe coupler for railway cars, the combination of a coupler head, a support therefor, resilient means 95 coöperating with said support and head for yieldingly maintaining the latter in position, means for adjusting the head longitudinally of the support and means for shifting said support transversely to the 100 longitudinal axis of the car.

14. In an automatic train pipe coupler for railway cars, the combination of a head, a spring for extending the head, an abutment for the spring, and means for shifting 105 the longitudinal axis of the abutment to a position approximately transverse to the longitudinal axis of the car.

15. In an automatic pipe coupler, the combination of a fixed bracket having longitudinal ribs, an extension pivoted to said fixed bracket and having ribs adapted to aline with the aforesaid ribs, a support comprising clamp members embracing said ribs of the fixed bracket and slidably therefrom upon the ribs of the extension, a coupling head carried by said support, means to positively move the support and head longitudinally of the fixed bracket and extension, and means to clamp said support to the 120 fixed bracket. 110

16. In an automatic pipe coupler, the combination of a fixed bracket, an extension pivoted to the fixed bracket, said bracket and extension being provided with rack 125 teeth, a clamping support movable along the bracket and extension, a coupling head carried by the support, and a power pinion journaled in the support in coöperation with said rack teeth for positively moving the 130

support and head along said bracket and extension.

17. In an automatic pipe coupler, the combination of a fixed bracket, an extension pivoted to the fixed bracket, said bracket and extension being provided with rack teeth, a clamping support movable along the bracket and extension, a coupling head carried by the support, a power pinion journal naled in the support in coöperation with said rack teeth for positively moving the support and head along said bracket and extension, means to control the reverse rotation of the pinion, and means to clamp the support to the fixed bracket.

18. In an automatic train pipe coupler for railway cars, the combination of a coupler head, a support therefor, and means for effecting relative movement between the support and head comprising a rack secured to one of said parts and a pinion rotatably mounted on the other member and engaging the rack.

In testimony whereof I affix my signature in presence of two witnesses.

JOSEPH VINCENT ROBINSON.
